FINISHING WELT

Filed July 8, 1929

Inventor
Robert C. Schemml,

By M. E. Dyer.

Attorney

UNITED STATES PATENT OFFICE

ROBERT C. SCHEMMEL, OF UNION CITY, INDIANA

FINISHING WELT

Application filed July 8, 1929. Serial No. 376,789.

My present invention relates to improvements in welts, bindings, mouldings and finishing strips used in trimming automobile bodies and tops and especially in upholstering the interiors thereof.

Such welts are commonly made of a base portion on which are superposed two or more longitudinal beads encased in a continuation of the fabric material which forms the base

portion, for the purpose of concealing, when the welt is in final applied position, the nails, tacks or other fastening means employed to secure the welt to the structure to be trimmed. Such welts are known as "blind nail" welts, and since the issuance of United States Letters Patent No. 1,226,600 to me on May 15, 1917, have been made in a variety of shapes and types and of many different materials.

It is frequently desirable to provide welts with bead coverings of contrasting colors to harmonize with an automobile interior done in two colors, or, when the welt is to be applied to the outside top of a vehicle, to produce a trimming in a plurality of colors and/or materials which will harmonize with the different colors of the body finish and upholstery.

In all the welt constructions of the prior art with which I am acquainted, the several beads which are attached to the welt base portion are necessarily encased or enveloped in a single continuous strip of covering material. When, therefore, it has been desired to produce a welt having its several beads enclosed in fabric of dissimilar materials or of contrasting colors, it has been necessary to apply a paint or dye to the bead covering of the finished welt to simulate different materials or produce different colors, a procedure of obviously low efficiency and high cost.

It is therefore an object of my present invention to provide a welt of the character indicated wherein the several beads are encased in a plurality of separate covering materials disposed in a novel series of folds which permits the seam along which the different covering materials are joined together to be concealed from view when the welt is in

its applied finished position on the supporting structure to be trimmed.

With these and other objects in view, my present invention consists, in certain forms of embodiment selected by way of exemplification, in the novel welt structure illustrated in the annexed drawing, described herein and particularly pointed out in the appended claims.

In the accompanying drawing which forms part of this application for Letters Patent, and in which the same reference numerals indicate like parts in the several views,

Figure 1 is a perspective view, in section at one end, of one type of welt constructed according to the principle of my present invention; and

Figs. 2 and 3 are similar views of two other types of welt illustrating further applications of the principle of my present invention.

Referring to the drawing, the reference numeral 1 thereon designates the customary relatively large half round bead which coacts with one or more smaller beads 2, in the types of welt which I have chosen to illustrate an application of my present invention, to conceal the tacks or other fastening means used to secure the welt in place on the supporting structure to be trimmed. 3 indicates a filler strip having incorporated therein pliable metallic weft strands which is secured to the large bead and anchored in the base portion of the welt to provide a pliable hinging member to hold the large bead down upon the base portion after the fastening tacks have been driven home, as particularly described and covered in my previously issued United States Letters Patent No. 1,719,729, dated July 2, 1929. By the term "base portion" I refer to the assembly of parallel, contacting fabrics disposed underneath the hinged bead and intended to immediately overlie the structure to be trimmed.

The large bead 1 is encased in a flexible fabric covering 4 of any desired material and color, which, according to my present invention, terminates along any convenient lines in the base portion of the welt. In the drawing I have indicated the terminal edges of

the fabric covering 4 by the reference numeral 5. It will be noted that in the case of each of the different types of welt shown in the drawing, the covering 4, before terminating in the edges 5, is disposed in two parallel, spaced apart layers in the base of the welt.

The smaller bead 2, whether occurring singly or doubly in the welts shown in the different figures, is encased in a covering fabric 6, which in the case of each welt is continued into two parallel, spaced apart layers in the base of the welt to terminate in the edges 7.

Unlike the bead coverings of the prior art, which are single unitary pieces for all the beads of a given welt, the covering 6 of a welt constructed according to the present invention, as will be noted by reference to the drawing, is a distinct and separate piece of fabric from that forming the covering 4. The several beads of a single welt being therefore encased in as many distinct and different pieces of fabric, it is obvious that in the production of a welt according to the present invention, the coverings 4 and 6 may be formed of different materials, or of the same material in different colors, to achieve the object of this invention in an entirely satisfactory and inexpensive manner. It will also be apparent that the hereinbefore described method of uniting the different fabrics in the base portion of the welt provides an effective concealment of the seam from view and a means of protection therefor against accidental loosening. It should be observed that the various fabric components of the base portion are preferably cemented together, according to the common practice in welt making.

While I have shown and described my present invention in connection with a limited number of different types of finishing welts, all of which embody the pliable wire wefted fabric forming the subject of my prior Patent No. 1,719,729, it is to be understood that the selection of these welts is only by way of illustration of my present invention. The present invention is applicable to many other and different types of welts, being capable of incorporation in any welt having a base portion and more than a single superposed bead. The appended claims are therefore to be construed broadly and without limitation to the specific types of welts herein shown and described.

Having thus described my present invention what I claim and desire to secure by Letters Patent is:

1. A blind nail finishing welt comprising a pair of spaced apart base fillers, a base fabric encasing said fillers and having a free edge therebetween positioned close to one of the fillers, a flap filler, a separate strip of fabric encasing said flap filler and having its free margins extended from one edge of the flap

filler, then folded back beneath the flap filler, terminating in interfitted relation with the free edge of the base fabric, and a line of stitching passing through the base and flap fabrics adjacent the free edge of the base fabric to unite the base and flap securely together in hinged relation near said last mentioned base filler.

2. A blind nail welt including a flap bead and a base bead, a fabric encasing the flap bead and terminating beneath said bead in a pair of parallel plies, a separate fabric enclosing the base bead having both of its margins terminating beneath said flap bead in parallel interfitted relation with the margins of said flap bead-enclosing fabric and cooperating therewith to form a base having at least four plies, and a line of stitching uniting said four plies near one edge of the four-ply portion of the base and forming a hinge connection for the flap bead and base.

In testimony whereof I affix my signature.
ROBERT C. SCHEMMEL.
